(57) **CLAIM**

The ornamental design for a removable cover for a respiratory mask, as shown.

DESCRIPTION

FIG. 1 is a front perspective view of removable cover for a respiratory mask, shown in the environment of use;

FIG. 2 is a front perspective view of the removable cover for a respiratory mask;

FIG. 3 is a front view thereof;

FIG. 4 is a side view thereof;

FIG. 5 is a top view thereof;

FIG. 6 is bottom view thereof;

FIG. 7 is a rear view thereof; and,

FIG. 8 is a rear perspective view thereof.

The broken line showing of the respiratory mask in FIG. 1 depicts the environment of the claimed design and forms no part thereof. All other broken lines depict portions of the removable cover for a respiratory mask that form no part of the claimed design.

1 Claim, 8 Drawing Sheets
